UNITED STATES PATENT OFFICE.

NATHAN C. ESTES, OF SMITHFIELD, RHODE ISLAND, ASSIGNOR OF ONE-HALF
TO J. & J. MURDOCK, OF LEICESTER, MASSACHUSETTS.

CARD-SETTING-MACHINE REST.

SPECIFICATION forming part of Letters Patent No. 404,036, dated May 28, 1889.

Application filed March 25, 1889. Serial No. 304,645. (No model.)

To all whom it may concern:

Be it known that I, NATHAN C. ESTES, a citizen of the United States, residing at Smithfield, in the county of Providence and State of Rhode Island, have invented a certain new and useful Improved Card-Setting-Machine Rest; and I do hereby declare that the following is a full, clear, and exact description thereof, which, in connection with the drawings making a part of this specification, will enable others skilled in the art to which my invention belongs to make and use the same.

My invention relates to card-setting machines used in the manufacture of card-clothing, and more particularly to the rest used in card-setting machines which supports the wires as the second bend is being made in the wires.

The object of my invention is to improve upon the present construction of the rest in a card-setting machine and to make the part on which the wires rest movable and adjustable; and my invention consists in certain novel features of construction of the rest and its connecting parts, as will be hereinafter fully described, and the nature thereof indicated by the claims.

In card-setting machines of the class to which my invention relates the wire after receiving its first bend is thrust through the clothing, and the two ends project out from the clothing and extend over and bear on a rest, which furnishes a firm edge to support the wires while the second bend is being made in the wires. The rest on which the wires are supported when the second bend is being made has heretofore been made stationary laterally, and the card-clothing is moved back and forth in front of said rest as the wires are inserted. The two ends of the wire, after being thrust through the clothing, always extend over the same points in the upper edge of the rest as the second bend is being made in the wires, all in the well-known manner familiar to those using card-setting machines.

It has been found in practice, and especially where steel wire is used in a card-setting machine, that by reason of the wires always extending over the same points in the upper

edge of the rest as the second bend is being made in the wires a slight depression or groove will be made in the top edge of the rest at the points where the wires bear, which will increase by the continued use of the machine, and it is necessary to constantly remove the rest to grind down the bearing-edge thereof and remove the depressions or grooves therein made by the wires, in order to make the edge of the rest true and even, so that the bends in the wires will be made uniform and the card-clothing be properly made.

My present invention is designed to overcome the necessity of constantly removing the stationary rest for the purpose of grinding out the depressions or grooves made in the bearing-edge thereof by the wires, and I carry out my invention by combining with the stationary rest and its supporting stand or frame of ordinary construction a thin blade or sheet of hardened steel, which is movable laterally and adjustable, and the upper edge of which serves as the rest on which the wires are supported and bear when the second bend is being made in the wires.

When by the constant wear of the wires depressions or grooves are made in the wearing edge of the supplemental rest, said rest is moved back or forth laterally or endwise on the stationary rest, so as to present an even and true edge, and also new points of wear for the wires.

When the supplemental rest has a number of depressions or grooves in its wearing edge, it is removed and replaced by a new one, the expense of the same being small.

Referring to the drawings, Figure 1 represents a plan view of a rest and its supporting-stand used in card-setting machines detached and with my improvements applied thereto. Fig. 2 is a vertical section on line $x x$, Fig. 1, looking in the direction of the arrow, same figure; and Fig. 3 represents the movable supplemental rest-blade detached.

In the accompanying drawings, 1 is the stand or frame, of the ordinary construction used in card-setting machines of the class to which my improvements relate, and adapted to be secured in its proper position in said machine. The upper end of the stand or frame

1 is made U-shaped, (see Fig. 1,) and upon the forward ends of the U-shaped part of said stand is supported and secured the stationary rest 2, of the ordinary construction, having 5 the vertical rest-blade 2' or rest proper, and the rearward-projecting arms 2'', extending at right angles from the ends of said rest-blade 2'. The arms 2'' have slots 3 therein to permit of moving the rest 2 back and forth 10 on its supporting-frame, and said arms are secured to the stand or frame 1 by screws 4, all of the ordinary and usual construction and operation in the class of card-setting machines to which my invention relates.

15 It will be understood by those skilled in the art that the wires as the second bend is being made in them extend over and are supported upon the upper edge of the rest-blade 2', as indicated by dotted lines 5, Figs. 1 and 20 2, and it will be observed that by means of the slots 3 in the arms 2'' of the rest 2 and the screws 4 the rest may be moved forward and back on the supporting-stand 1 and adjusted toward or away from the wires and 25 the cloth in which they are secured to make the bend in the wires shorter or longer, as desired. It will also be observed that there is no lateral motion to the rest 2 on its supporting-stand, and that the wires 5 will always 30 extend over the same points in the upper edge of the rest-blade 2'.

As heretofore stated, by reason of the wires extending over the same points in the upper edge of the rest-blade 2', depressions or 35 grooves are soon worn in said blade, and it is necessary to constantly remove the entire rest 2 and to grind out said depressions or grooves or substitute a new rest.

In my invention I combine with the rest 2 40 and the stationary rest-blade 2' a supplemental movable rest-blade, 6, which is adjustable laterally or endwise.

The supplemental rest-blade 6 is preferably made of a thin piece or sheet of hardened 45 steel, and is placed edgewise immediately behind the rest-blade 2', resting on the arms 2'' and bearing against the inner surface of the rest-blade 2'.

The supplemental rest-blade 6 is made suffi- 50 ciently wide so that the upper edge will extend above the upper edge of the rest-blade 2', and the wires will rest and be supported upon the upper edge of the supplemental rest-blade 6 and not upon the upper edge of the rest-blade 2'.

The supplemental rest-blade 6 is secured in place and held firmly against the rest-blade 2' in this instance by means of the two wedge-pieces 7 and the holding-screws 8. The rear 55 lower edge of each wedge-piece 7 is made beveled, and is adapted to bear against a shoulder, 9, made in the upper surface of the arms 2'' of the rest 2', and the front edge of each wedge-piece 7 is made slightly beveled and 60 is adapted to bear against the inner surface of the supplemental rest-blade 6. (See Fig. 2.) 65 By screwing in the screws 8 the front edge of

the wedge-pieces 7 is drawn down and made to bear against the inner surface of the supplemental blade 6 and hold the same firmly 70 against the rest-blade 2', and by screwing out the screws 8 the front edge of the wedge-pieces 7 is released, allowing the supplemental rest-blade 6 to be moved laterally or endwise, or to be removed entirely. 75

I have shown in the drawings and described above one way of securing the supplemental rest-blade 6 to the rest-blade 2'; but it will be understood that any other equivalent or well-known way of securing the same may be employed, as by means of a clamp-screw, a cam-wedge, &c.

If preferred, the details of construction of the rest proper and the supplemental rest-blade and the manner of combining the same 85 together may be varied somewhat from what is shown and described. For instance, instead of a blade or thin sheet of metal to serve as a supplemental rest, I may employ a circular piece or disk supported on the rest proper 90 or on the frame and adapted to revolve to present new points of wear for the wires as the second bend is being made in the same.

The operation of the movable supplemental rest-blade 6 will be readily understood by 95 those skilled in the art.

The wires are supported by and rest upon the top edge of the supplemental rest-blade 6 as the second bend is being made in the wires. When depressions or grooves are 100 made in the upper edge of the supplemental rest-blade 6 by reason of the wires always extending over the same points in said edge, as above described, the holding-screws 8 are loosened and the wedge-pieces 7 released, so 105 that the supplemental rest-blade 6 may be moved back or forth laterally or endwise to present new points on its upper edge for the wires to rest upon. The screws 8 are then tightened and the supplemental rest-blade 6 110 clamped in its new position.

When the upper edge of the supplemental rest-blade 6 is full of depressions or grooves, the blade may be reversed and the lower edge made the upper edge; or a new blade may be 115 substituted.

The advantages of my invention will be readily appreciated by those skilled in the art. The supplemental movable rest-blade 120 may be applied to the stationary rest of ordinary construction now in general use in the class of card-setting machines to which my invention relates without changing the construction of said stationary rest or the stand or frame upon which it is supported. 125

By the use of the supplemental movable rest-blade a large number of new points of wear for the wires may be obtained, thus avoiding the necessity of grinding out or removing the depressions or grooves made in the blade, making it much less expensive and much less labor for the operator, and procuring a greater uniformity in the work. 130

Having thus described my invention, what

I claim as new, and desire to secure by Letters Patent, is—

1. In a card-setting machine, the combination, with the rest and its supporting-frame, 5 of a supplemental adjustable rest adapted to present new points of wear for the wires which are supported thereon when the second bend is being made, substantially as set forth.
2. In a card-setting machine, the combination, 10 with the rest adjustable back and forth on its supporting-frame, of a supplemental rest-blade adjustable laterally or endwise and means for securing the same to the rest, substantially as and for the purpose stated.

3. In a card-setting machine, the combination, 15 with the rest adjustable back and forth on its supporting-frame and means for securing it in place, of a supplemental rest-blade movable laterally or endwise on said rest and wedge-pieces and holding-screws for securing 20 said supplemental rest in place, substantially as shown and described.

NATHAN C. ESTES.
